VACUUM CLEANER

Original Filed Dec. 9, 1938

2 Sheets-Sheet 2

An exploded view diagram of a cylindrical mechanical assembly. The main body is a large cylinder with a ribbed outer surface. Several parts are shown in an exploded configuration around it. On the left, a rectangular plate 60 is attached to a lever 54, which is connected to a small cylinder 36. A rod 48 extends from the top of the main cylinder. A ring 50 is positioned on the cylinder, with part 44 attached to its inner edge. A large, flat, circular plate 58 is shown at the bottom, with part 56 attached to its outer edge. A small cylinder 36 is also shown attached to the side of the main cylinder. Various other parts, including 16, 46, 52, 70, 38, 34, 68, and 60, are labeled throughout the diagram.

VACUUM CLEANER

Oscar M. Anderson and Nils T. Almquist, New Britain, Conn., assignors to Landers, Frary & Clark, New Britain, Conn., a corporation of Connecticut

Original application December 9, 1938, Serial No. 244,830. Divided and this application October 31, 1940, Serial No. 363,656

7 Claims. (Cl. 230—117)

The present relates to vacuum cleaners and more particularly to a new and improved type of motor support therefor. The present application is a division of application, Serial No. 244,830, filed December 9, 1938, and relates to the motor mounting shown in the aforementioned application.

The object of the present invention is to provide an improved motor mounting which cushions the motor and absorbs shocks which would otherwise be transferred thereto while the cleaner is in use.

Another object is to provide a motor mounting which permits ready assembly or removal of the motor and fan unit from the vacuum cleaner casing.

Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

In the accompanying drawings:

Figure 1 is a longitudinal sectional view of a vacuum cleaner utilizing a motor mounting of the type embodying the invention herein;

Fig. 2 is an end view partly in section of the motor mounting in its assembled position within the vacuum cleaner unit; and

Fig. 3 is a perspective view of the motor mounting bushing and supporting spiders therefor.

Referring to the drawings, there is shown for purposes of illustration a vacuum cleaner of the portable tank type for which the motor mounting constituting the present invention is particularly adapted. The cleaner comprises generally a casing 10, runners 11 for normally supporting the casing in a horizontal position, a vacuum creating unit including a motor 12, a rotary suction pump or exhaust fan 14, an air filter 16, a supporting and sealing gasket 17, a dust bag 18, and a forward end closure 20. The casing 10 is substantially cylindrical at the dust bag end and of such size that the mechanism may be readily removed or inserted therethrough; whereas at its opposite end it is of reduced diameter and is provided with an inturned annular flange 22, and extending rearwardly from the inner periphery of the flange 22 is a substantially conical portion 24 terminating in a cylindrical flange or ring 26 to which the motor mounting may be supported as is hereinafter apparent.

In order to give a finished appearance to the 55 members, or the sections may be assembled di-

casing, there is further provided a cap 28 which encloses the conical portion 24 of the casing and is secured as by bolts 30 to the annular flange 22.

The details of the aforementioned structure 5 are all fully disclosed in the above-mentioned application, and no further reference will be made to them except when necessary to an understanding of the invention herein.

In accordance with the present invention, the 10 motor mounting, which is generally designated as 32, comprises a bushing 34 and a spider 36 extending outwardly from the bushing and securable to the vacuum cleaner casing. More particularly, the bushing 34 is made of rubber or 15 any other resilient material and is provided with a central opening 38 whereby the bushing may be tightly fitted onto a bearing surface 40 extending rearwardly from the housing 42 of the motor 12. The bushing is of cylindrical form, 20 and its outer periphery has cut therein a groove 44 to provide spaced annular ribs 46.

Positioned within the groove 44 are a plurality 25 of holding members 48, each including an arcuate portion 50 terminating at one end in a short radially extending securing lug 52 and at its other end in a long spacing arm 54. In the embodiment illustrated, three holding members are provided; each extending through approximately 120°, whereby the leg 52 of one holding member 30 abuts the spacing arm of the next holding member, whereupon the two may be secured by a suitable screw 58 extending through aligned openings for receiving same. When so secured, the spacing members provide in effect a complete 35 circumferential holding ring or hub carrying the three radially extending spacing arms 54. Each spacing arm 54 in turn terminates in a laterally extending securing lug 60 adapted to abut against the circumferential flange 26 carried on the rear 40 end of the conical portion 24 of the casing 10. When properly aligned with the flange, the lug 60 may be secured thereto by suitable screws 62 extending through aligned openings provided in the members.

45 From the foregoing it will be seen that each holding member may be readily stamped from any suitable metal and then quickly assembled onto the bushing 34 and, when so assembled, kept in proper position by the ribs 46 to each side 50 of the groove 44. The holding members are so constructed that they may either be assembled into the completed spider and then mounted on the bushing by distorting same and then snapping it into the band formed by the holding

members, or the sections may be assembled di-

rectly onto the bushing. Due to the fact that a resilient distortable bushing is used, the spider could, of course, be made of one piece. With the spider assembled on the bushing, the latter may be mounted on the bearing part of the motor by simply forcing it thereon. When so positioned, the bushing may be held in place by an end plate 64 bearing against the end of the bushing and secured to the motor bearing portion by a screw 66. Upon insertion of the motor within the casing, the spider may be readily secured to the flange 26 of the casing. To give further resiliency to the bushing, the body portion may also have a plurality of openings 68 cut therein in axial alignment with the bearing opening 38.

In the embodiment illustrated, the bushing 34 is also provided with a rearwardly extending peripheral ridge 70 which cooperates with the circumferential ridge 46 to provide a shoulder support for one end of a screen filter 72, which filter has its forward end supported on a circumferential shoulder 74 extending rearwardly from the cap member 28.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

We claim as our invention:

1. In a vacuum cleaner, a generally cylindrical exterior housing, means for normally supporting it in generally horizontal position, a motor and fan assembly entirely contained therein, and means for securing said motor and fan assembly to said housing, including a ring engaging an end of the housing, a spider in said ring, a generally central hub in said spider, the motor assembly including a portion penetrating said hub, a supporting element of yielding compressible material interposed between said hub and the penetrating portion of said motor, a fan housing secured to said motor assembly, and a slideable supporting connection between said fan housing and the interior of said cylindrical housing, including a rubber washer secured to said fan housing and adapted to act as a seal between said fan housing and the inner face of said cylindrical housing.

2. In a vacuum cleaner, a generally cylindrical exterior housing, means for normally supporting it in generally horizontal position, a motor and fan assembly entirely contained therein, and means for securing said motor and fan assembly to said housing, including a ring engaging an end of the housing, a spider in said ring, a generally central hub in said spider, the motor assembly including a portion penetrating said hub, a fan housing secured to said motor assembly, and a slideable supporting connection between said fan housing and the interior of said cylindrical housing, including a rubber washer secured to said fan housing and adapted to act as a seal between said fan housing and the inner face of said cylindrical housing.

3. In a vacuum cleaner, a generally cylindrical

exterior housing, means for normally supporting it in generally horizontal position, a motor and fan assembly entirely contained therein, and means for securing said motor and fan assembly to said housing, including a ring engaging an end of the housing, a generally central hub, and means for supporting it in said ring, the motor assembly including a portion penetrating said hub, a supporting element of yielding compressible material interposed between said hub and the penetrating portion of said motor, a fan housing secured to said motor assembly, and a slideable supporting connection between said fan housing and the interior of said cylindrical housing, including a rubber washer secured to said fan housing and adapted to act as a seal between said fan housing and the inner face of said cylindrical housing.

4. In a vacuum cleaner, a generally cylindrical exterior housing, means for normally supporting it in generally horizontal position, a motor and fan assembly entirely contained therein, and means for securing said motor and fan assembly to said housing, including a ring engaging an end of the housing, a generally central hub, and means for supporting it upon said ring, the motor assembly including a portion penetrating said hub, a fan housing secured to said motor assembly, and a slideable supporting connection between said fan housing and the interior of said cylindrical housing, including a rubber washer secured to said fan housing and adapted to act as a seal between said fan housing and the inner face of said cylindrical housing.

5. In a vacuum cleaner, a generally cylindrical exterior housing, means for normally supporting it in generally horizontal position, a motor and fan assembly entirely contained therein, and means for securing said motor and fan assembly to said housing, including a ring engaging an end of the housing, a generally central hub, and means for supporting it upon said ring, the motor assembly including a portion penetrating said hub, a fan assembly secured to said motor assembly, and a slideable supporting connection between said fan assembly and the interior of said cylindrical housing, including a rubber washer secured to said fan assembly and adapted to act as a seal between said fan housing and the inner face of said cylindrical housing.

6. In a vacuum cleaner having a cylindrical housing normally supported in generally horizontal position, a motor entirely contained therein, and means for securing said motor to said housing and comprising a ring engaging an end of the housing, a spider in said ring, a generally central hub in said spider, the motor including a portion penetrating said hub, and a supporting element of yielding compressible material interposed between said hub and the penetrating portion of the housing.

7. In a vacuum cleaner having a cylindrical housing normally supported in generally horizontal position, a motor entirely contained therein, and means for securing said motor to said housing and comprising a supporting element of yielding compressible material, a portion on said motor penetrating said supporting element, a spider including a central hub in which said compressible element is supported, and means carried by the spider and radially spaced from said hub and securing said spider to said housing.
